(57) **CLAIM**

The ornamental design for a puck lock holder, as shown and described.

DESCRIPTION

FIG. 1 is a top perspective view of a first embodiment of a puck lock holder showing my new design;

FIG. 2 is a bottom perspective view of the first embodiment of the puck lock holder;

FIG. 3 is a left side view of the first embodiment of the puck lock holder;

FIG. 4 is a front view of the puck lock holder of FIG. 1;

FIG. 5 is a rear view of the puck lock holder of FIG. 1;

FIG. 6 is a top view of the puck lock holder of FIG. 1;

FIG. 7 is a bottom view of the puck lock holder of FIG. 1;

FIG. 8 is a left side cross-sectional view taken along line 8-8

of FIG. 6 in an alternate disclaimed example environment;

FIG. 9 is a top perspective view of a second embodiment of the puck lock holder;

FIG. 10 is a bottom perspective view of the puck lock holder of FIG. 9;

FIG. 11 is a left side view of the puck lock holder of FIG. 9;

FIG. 12 is a front view of the puck lock holder of FIG. 9;

FIG. 13 is a rear view of the puck lock holder of FIG. 9;

FIG. 14 is a top view of the puck lock holder of FIG. 9;

FIG. 15 is a bottom view of the puck lock holder of FIG. 9;

and,

FIG. 16 is a left side cross-sectional view taken along line 14-14 of FIG. 14 in an alternate disclaimed example environment.

Right side views not shown are mirror images of left side views. Broken lines shown are included for the purpose of illustrating portions of the puck lock holder that form no part of the claimed design. Broken lines shown in FIGS. 8 and 16 depict environment that forms no part of the claimed design.

1 Claim, 12 Drawing Sheets
